INVENTOR

UNITED STATES PATENT OFFICE.

JOHN A. HALLOWAY, OF NEW YORK, N. Y.

MUSICAL WIND INSTRUMENT.

No. 902,290.

Specification of Letters Patent.

Patented Oct. 27, 1908.

Application filed March 23, 1908. Serial No. 422,800.

To all whom it may concern:

Be it known that I, JOHN A. HALLOWAY, a citizen of the United States, residing in the borough of Manhattan, of the city of New York, in the State of New York, have invented certain new and useful Improvements in Musical Wind Instruments, of which the following is a specification, reference being had to the accompanying drawings, forming a part hereof.

This invention relates to improvements in wind instruments having a sliding member, same as the trombone; the object being, 1st, to lengthen the service of said instrument; 15 2nd, to lessen the amount of oiling necessary to obtain the proper working of the sliding part or slide as it is generally called; 3rd, to insure cleanliness of the instrument by preventing the oil used in the lubrication of the 20 parts from being scraped off from the central member and being transferred to the outside of the slide where, owing to the construction that has been hitherto employed, the oil or lubricant has made this instrument very ob- 25 jectionable, as the hands of the player soon become soiled from the grease or oil which has been deposited on the outside of slide, and the clothing, and particularly the shirt front soon becomes spattered by the opera- 30 tion of the slide.

In accordance with the present invention, means are provided so that no grease or lubricant passes to the outside of the moving slide, and in consequence the instrument is 35 rendered as clean as any other instrument of an orchestra.

In the accompanying drawings, Figure 1 is a side view of a trombone embodying the invention; Fig. 2 is a view on a larger scale of 40 the portion of the instrument in which the invention applies, the same showing only one leg of the mechanism, the portion of the slide being in section; Fig. 3 is also a view on a larger scale of the portion in which the invention 45 applies, both legs being shown in their relation to the mouth-piece, while a portion of one of the legs is shown in section illustrating one modified form of the diverging end of the bearing member.

50 Similar letters refer to similar parts throughout the several views.

Embodiment of my invention is shown in

my drawings, it being understood that various modifications may be made without departing from the spirit of my invention. 55

A designates what is called the slide, which is composed of two legs, each of which is designated *c*. Joining these two legs *c* is the connecting tie *g*; *f* designates the flaring ends of the legs *c*; *e* designates the cup-shaped 60 collars which form a part of the stationary pieces *d*, which act as plungers working inside of the two legs *c*. When the slide is in its innermost position the ends *f* telescope inside of the cups *e*, as shown by dotted position *a*.

B designates the stationary part of the instrument having one leg *b* and another leg *x*; which terminates in the bell end *l*, and the portion *h* carries the mouth-piece *m*. There 70 being sliding friction between the parts *d* which work inside of *c*, it is necessary to lubricate the bearing between the two.

Instead of leaving the end of the legs *c* square and sharp so as to scrape over the 75 surface of *d*, as hitherto practiced, I make the ends with flaring interiors which will act as receptacles or gatherers for the oil or lubricant, which would otherwise be scraped off from the surface of *d* and not only be lost for 80 the purpose intended, but soil the person of the player.

With my invention, the lubricant is redeposited on the tube *d* as it is withdrawn. The rounded surface at the ends will give a 85 smooth, sliding action between the two parts, and thus lessen the wearing of the parts in sliding contact.

What I claim as new and desire to secure by Letters Patent is:

1. A musical instrument having a sliding part telescoping inside another part, the ends of the outer tubular casing diverging from the bearing-fit for the purpose described.

2. A slide trombone, provided with cupped 95 ends on the tubular casing forming the slide for the purpose described.

In testimony whereof I have signed my name to this specification in the presence of two subscribing witnesses March 21, 1908. 100

JOHN A. HALLOWAY.

Witnesses:

GEORGE A. WARD,
MAURICE J. SULLIVAN.
